William F. Mahoney, Indianapolis, Ind., assignor to Indianapolis Reed Company, Incorporated, Indianapolis, Ind.

Application February 13, 1933. Serial No. 47,203

Term of patent 7 years

To all whom it may concern:

Be it known that WILLIAM F. MAHONEY, a citizen of the United States, residing at Indianapolis, in the county of Marion, and State of Indiana, has invented a new, original, and ornamental Design for Lawn Vases, of which the following is a specification, reference being had to the accompanying drawing forming part thereof.

In the accompanying drawing, the single figure is a view in perspective of a lawn vase, showing my new design.

I claim:

The ornamental design for a lawn vase as shown.

In testimony whereof I affix my signature.

WILLIAM F. MAHONEY.
